UNITED STATES PATENT OFFICE

LESLIE HURST PETER, OF LONDON, ENGLAND, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA

RAILWAY SIGNALING APPARATUS

Application filed October 17, 1931, Serial No. 569,458, and in Great Britain October 29, 1930.

My invention relates to railway signaling apparatus of the kind in which the signal comprises a movable semaphore arm or spectacle or both, and a continuously illuminated signal lamp adapted to be supplied with operating current from an alternating current supply circuit, which are arranged to cooperate to give the necessary signal indications.

The invention has for its object to provide improved arrangements for electrically indicating at the point of control the position of the signal arm or spectacle and whether or not the lamp is properly operative.

According to the principal feature of the invention the indicating device at the point of control which device is of the direct current polarized type is arranged to be supplied with unidirectional operating current through indication conductors leading to the signal from the point of control, this current being derived from the signal lamp circuit by means of full- or half-wave rectifiers.

The invention is illustrated by way of example in the accompanying drawing of which Figure 1 is a diagrammatic view of a signal comprising a semaphore arm or spectacle and provided with a system of indications embodying one form of the invention. Figures 2, 3 and 4 illustrate modified forms of the electrical arrangements of the system of Figure 1, and Figure 5 illustrates the invention as applied to a signal provided with an auxiliary signal lamp.

Referring now first to the apparatus illustrated in Figure 1 it will be seen that the signal comprises a semaphore arm 1 and a spectacle arm 2 combined with a continuously illuminated signal lamp 3 supplied with current from the secondary winding 4 of a transformer 5, the primary winding 6 of which is connected to an alternating current supply circuit.

A suitable series resistance 7 is included in the circuit of the lamp 3, the terminals or suitable points in the resistance 7 being connected by conductors 8, 9 to the in-put terminals of a full-wave rectifier 10 comprising four rectifying units or sets of units arranged in the well-known bridge connection.

The out-put terminals of the rectifier 10

are connected by means of conductors 13, 14 to a pair of indication conductors 11, 12, extending to the signal from the point of control through a circuit breaker device 15 operated by the signal arm 1. The circuit breaker device comprises contact arms 17, 18 so arranged that when the signal arm 1 and the spectacle 2 move from the normal or "stop" position shown, to the reverse or "proceed" position or vice versa, the circuit breaker 15 reverses the connections of the rectifier 10 to the indication conductors 11, 12. For example, when the signal occupies its "stop" position as shown the contact arms 17, 18 of the device 15 connect the conductors 13, 14 to the indication conductors 11, 12 respectively so that current of positive polarity is supplied to these conductors whereas when the signal moves to its reverse or "proceed" position the contact arms 17, 18 connect the conductors 14, 13 to the indication conductors 11, 12, respectively so that current of negative polarity is supplied to the conductors 11, 12.

At the point of control an indicating device 19 is provided and adapted to occupy one or other of three different positions according to whether the indication conductors 11, 12 are deenergized or are supplied with current of positive or negative polarity. Under normal conditions, that is to say, when the signal arm 1 is in its "stop" position, the current of positive polarity supplied to the indication conductors 11, 12 will cause the indicating device 19 to give the indication "signal on" while when the signal arm 1 is moved to its reverse position, indicating "proceed," the indicating device 19 at the point of control will correspondingly indicate "signal off."

In the event of the signal arm 1 or the spectacle 2 occupying any other position the connection of the rectifier 10 to the indication conductors 11, 12 will evidently be interrupted at the contact arms 17, 18 of the circuit breaker device 15, with the result that the indicating device 19 will be deenergized and will indicate "signal wrong." The indication conductors 11, 12 will also be evidently deenergized in the event of failure of the circuit of the lamp 3 since under these conditions

the resistance 7 will not be traversed by current.

In a modified arrangement the indicating device 19, instead of being directly connected to the indication conductors 11, 12 may be arranged to be controlled by means of a polarized relay, the energizing winding of which is connected to these conductors as will be obvious without further explanation.

10 Referring now to the indication system shown in Figure 2 separate indication devices 19, 20 for the signal arm 1 or spectacle 2 and for the lamp 3 are provided. The indicating device 20 for the lamp 3 is similar to that 15 above described, a series resistance 7 being connected in the lamp circuit, the terminals or intermediate points in this resistance being connected by conductors 21, 22 to the in-put terminals of a full-wave rectifier 23. The 20 out-put terminals of the rectifier 23 are directly connected to a pair of indication conductors 24, 25 leading to the point of control and the lamp indicating device 20 is connected to these conductors and is adapted to give 25 one or other of two indications according to whether the device 20 is energized or not. So long as the circuit of the lamp 3 is intact and current for illuminating the lamp is being properly supplied thereto, the rectified 30 current supplied to the indication conductors 24, 25 will cause the lamp indicating device 20 to be energized and to give an indication "lamp in," whereas any failure in the lamp circuit or in the source of supply thereto will 35 cause the indication conductors 24, 25 to be deenergized so that the indicating device 20 will give the indication "lamp out". The other device 19 for indicating the position of the signal arm 1 or spectacle 2 is similar to 40 that described with reference to Figure 1 and is connected to the signal by the indication conductors 11, 12 which are connected to the signal through the circuit breaker device 15 operated by the signal arm 1 and the full- 45 wave rectifier 10 which is supplied with current from a second secondary winding 26 on the transformer 5 through which the signal lamp S is supplied with current. The indicating device 19 will accordingly give an indication "signal arm on" or "signal arm off", according to whether the circuit breaker device 15 connects the rectifier conductors 13, 14 50 to the indication conductors 11, 12 in the normal or reverse direction, while in the event 55 of the signal arm 1 or the spectacle 2 occupying any other position the indicating device 19 will be deenergized and will indicate "signal wrong".

Referring now to the system shown in Figure 3, the circuit breaker device 15 is provided with only a single contact arm 16. The indication conductor 11 is directly connected to one terminal of the series resistance 7 in the circuit of the lamp 3 while the other indication conductor 12 is connected through the

contact arm 16 of the circuit breaker device 15 to one or other of two oppositely arranged half-wave rectifiers 27, 28 which are connected to the other terminal of the series resistance 7.

With this arrangement it will be evident that current is supplied from the series resistance 7 through the rectifier 27 or the rectifier 28 to the indication conductors 11, 12, according to whether the signal arm 1 occupies its "stop" or "proceed" position.

Referring now to the system shown in Figure 4 the series resistance utilized in the system of the preceding figures is replaced by a pair of current transformers 29, 30, the primaries 31, 32 of which are connected in the circuit of the lamp 3 while their secondary windings 33, 34 are connected to the in-put terminals of two full-wave rectifiers 35, 36 respectively.

The out-put terminal 37 of the rectifier 35 and the opposite out-put terminal 38 of the rectifier 36 are connected directly to the indication conductor 12 while the out-put terminal 39 of the rectifier 35 or the out-put terminal 40 of the rectifier 36 is arranged to be connected to the indication conductor 11 according to whether the contact arm 16 of the circuit breaker device 15 is in the position shown corresponding to the "stop" position of the signal arm or in its opposite or "proceed" position.

In the former case current of positive polarity will evidently be supplied through the rectifier 35 to the indication conductors 11, 12 whereas in the latter case these conductors will be supplied with current of negative polarity through the rectifier 36.

Referring now to the system shown in Figure 5 the signal is shown as provided with an auxiliary lamp 41 adapted to replace the lamp 3 in the event of the latter failing for any reason. The main lamp 3 is arranged to be supplied with current from the secondary winding 4 of a transformer 5, the primary winding 6 of which is connected to supply circuit conductors 42, 43, one 43 of which serves as a return conductor for the indication device 19. The circuit of the lamp 3 includes the winding of a relay 44, across the terminals of which a rectifier 45 is connected and the contact arm 46 of the relay 44 is arranged to engage with a fixed contact 47 so long as the relay is energized whereas when the relay is deenergized the contact arm 46 engages with a fixed contact 48.

In operation it will be understood that so long as the lamp 3 is intact and operative, the relay 44 is energized by unidirectional current owing to the provision of the rectifier 45. The indication circuit is thus completed through the contact arm 46 and contact 47 of the relay 44. In the event, however, of failure of the lamp 3 the relay 44 is deener-

gized and a circuit is completed from the transformer winding 4 to the auxiliary lamp 41 by way of contact arm 46 and contact 48 of the relay 44. The lamp 41 is thus supplied with operating current but the indication circuit being interrupted, the indication device 19 is deenergized so as to indicate the failure of the main lamp 3.

5 The rectifiers employed as above described 10 are preferably of the metal compound type described in the specification of British Patent No. 194,653.

15 It will be understood that any of the arrangements above described in which half-wave rectifiers are employed may, if desired, be modified so that each rectifier is arranged to by-pass alternate half-waves of the alternating current instead of transmitting these 20 half-waves, the effect in either case being to supply a unidirectional pulsating current to the indication conductors.

25 The invention is evidently not limited to the particular arrangements described and illustrated by way of example which may be modified in various respects without exceeding the scope of the invention.

30 Having now particularly described and ascertained the nature of my said invention and in what manner the same is to be performed, I declare that what I claim is:

35 1. Railway signaling apparatus comprising a movable semaphore arm or spectacle and a continuously illuminated signal lamp adapted to be supplied with operating current from an alternating current supply circuit in which an electrical indicating device of the direct current polarized type is provided at the point of control and is arranged 40 to be supplied with unidirectional operating current through indication conductors, this current being derived from the signal lamp circuit through one or more rectifiers, for the purpose specified.

45 2. Railway signaling apparatus as claimed in claim 1 in which the rectifier or rectifiers is arranged to be connected to the indication conductors through a circuit breaker device operated in accordance with the position of the semaphore arm or spectacle, for the purpose specified.

50 3. Railway signaling apparatus as claimed in claim 1 in which the current supplied to the indication conductors is arranged to be derived from a resistance connected in the signal lamp circuit, for the purpose specified.

55 4. Railway signaling apparatus as claimed in claim 1 in which the current supplied to the indication conductors is arranged to be derived from the secondary winding or windings of a series transformer or transformers the primary winding or windings of which is connected in the signal lamp circuit, for the purpose specified.

60 65 5. Railway signaling apparatus as claimed

in claim 1 in which the rectifier or rectifiers are arranged to be connected to the indication conductors through a circuit breaker device operated in accordance with the position of the semaphore arm or spectacle, and in which the indication conductors are arranged to be connected through the circuit breaker device to one or other of two oppositely connected full or half-wave rectifiers, for the purpose specified.

6. Railway signaling apparatus as claimed in claim 1 in which separate devices are provided for indicating the condition of the signal lamp circuit and the position of the signal arm or spectacle, substantially as described.

7. In combination, a railway signal comprising a semaphore and a continuously lighted electric lamp, a polarized indication device, means included in the circuit of said lamp for supplying current to said device, and means operated by said semaphore for causing said current to be of one polarity or the other according to the position of the semaphore.

In testimony whereof I affix my signature.
LESLIE HURST PETER.
